UNITED STATES PATENT OFFICE.

OTHO M. OTTE, OF JAMESTOWN, NEW YORK.

REFLECTOR CUT-OFF FOR HEADLIGHTS.

1,289,244.

Specification of Letters Patent. Patented Dec. 31, 1918.

Application filed April 22, 1918. Serial No. 229,892.

To all whom it may concern:

Be it known that I, OTHO M. OTTE, a citizen of the United States, residing at the city of Jamestown, in the county of Chautauqua and State of New York, have invented certain new and useful Improvements in Reflector Cut-Offs for Headlights, of which the following, taken in connection with the accompanying drawings, is a specification.

10 The invention relates to automobile headlights and means for controlling the light from the same; and the improvement consists in providing a mechanical reflector cut-off for the upper portion of the parabolic reflector so that the reflection of the light is limited to a predetermined height, the cut-off being so arranged that the upwardly directed light rays are reflected back through the source of light to the lower portion of the 15 parabolic reflector so that the major portion of the light rays from the source of light are reflected upon the roadway as desired; and the invention consists in the novel features and combinations hereinafter set forth and 20 claimed.

In the drawings, Figure 1 is a vertical sectional view of the headlight or lamp showing the construction and arrangement of the parts, the control of the light rays being 25 shown by dotted line. Fig. 2 is a detail front perspective view of the reflector cut-off removed from the lamp; and Fig. 3 is a perspective view of the under and inner sides of the reflector cut-off showing the construction and arrangement of the same.

Like characters of reference refer to corresponding parts in the several views.

The numeral 10 designates a parabolic reflector lamp for automobiles which is constructed with substantially parabolic shaped outer casing 11. The casing 11 is arranged in spaced relation to the parabolic shaped reflector 12, a light post 13 being connected to the center of the reflector 12. The reflector 12 is supported by the outwardly turned flange 14 around the outer rim of the reflector 12 which flange 14 braces against the inner wall of the casing 11 thereby holding the outer rim of the parabolic reflector 12 45 and the casing 11 firmly in the attached position.

A glass 15 is provided to cover the front of the reflector 12, which glass is held in place by the inclosing rim 16. The rim 16 50 is attached to the casing 11 by spaced screws 17 around the periphery of the casing. A

groove 18 is provided in the outwardly turned flange rim 14 to receive therein a packing 19 against which the supporting rim 20 of the reflector cut-off 21 rests and thereby prevents all rattling as well as inclosing the interior of the reflector. The rim 20 also has a groove 22 with packing 23 therein which extends around the semi-circular rim 20 of the reflector cut-off 21, the glass 15 resting firmly against the packing 23 for the upper half of the reflector and against the packing 19 for the lower half, all the parts being held in their proper relation to one another by means of the inclosing rim 16. 60

The reflector cut-off 21 consists of the semi-circular rim 20 which is supported within the reflector 12 as hereinbefore described by means of the inclosing rim 16 65 pressing the packings 19 and 23 thereagainst. 70

A parabolic or semi-circular shaped cut-off plate 24 for the upper portion of the parabolic reflector is attached to the lower ends 25 of the rim 20 preferably by means of the angle brackets 26 and screws 27 and extends 80 into the parabolic reflector. The front edge 28 of the reflector cut-off plate 24 is turned downwardly with a central projection 29 to which the semi-circular name and screen plate 30 is attached. 85

The cut-off plate 24 is shaped to fit within the reflector 12 immediately above the light 33 and light post 13, inclining downward slightly toward the front of the reflector. A semi-circular bulbous shaped upward projection 32 is provided in the reflector cut-off 21 which fits immediately over the lamp bulb 31, the shape of the inner side of the bulbous portion 32 being so designed as to reflect the light rays back to the source of light 33 90 and through said source of light to the lower portion of the parabolic reflector 12 by which it is reflected in parallel alinement upon the roadway. The entire under surface of the reflector cut-off plate 24 is polished or coated with a reflecting material so as to reflect the rays of light downward as indicated in Fig. 1 with the exception that the central plate 30 cuts off the direct rays of light from the source of light 33. 95

100 It is apparent that this simple mechanical reflector cut-off utilizes a large portion of the light rays preventing their upward reflection above a given distance from the surface of the roadway, which reflector cut-off 110 may be manufactured at small cost and readily and easily attached within the dif-

ferent designs of parabolic reflector automobile headlights.

I claim as new:—

1. A reflector cut-off for electric headlights and the like, composed of an approximately horizontal plate of substantially semi-circular shape having an upwardly extending bulb-like part to receive the upper portion of the electric bulb, a substantially semi-circular rim secured to the upper half of the headlight reflector at the front of the latter, said rim having a semi-circular flange extending rearwardly thereof, angle-brackets having one arm secured to the flange at the ends thereof, and means to secure said plate to the other arms of the angle brackets, said plate having a central shield depending from the center thereof.
2. A reflector cut-off for electric headlights and the like, composed of an approximately horizontal plate of substantially semi-circular shape having an upwardly extending bulb-like part to receive the upper portion of the electric bulb, a substantially semi-circular rim secured to the upper half of the headlight reflector at the front of the latter, and means to secure the plate to the ends of said rim.
3. A reflector cut-off for headlights and the like composed of a substantially semi-circular ring-like member having a part clamped between the headlight glass and the reflector at the top portions of the same, said member also having a part extending into the reflector and engaging the latter to

hold the ring-like member in fixed position, a substantially semi-circular plate extending over the top of the light, and means to rigidly secure the plate to the ends of the ring.

4. A reflector cut-off for headlights and the like composed of a substantially semi-circular ring-like member extending around the top and adjacent side parts of the reflector, said member having front and rear depressed parts, packing in each of the depressed parts, the packing at the front being engaged with the headlight glass and the packing at the rear with the reflector, means to secure the headlight glass in place so as to clamp the member in position, a plate overlying the light, and means to secure the plate to the ends of the member.

5. A reflector cut-off for headlights and the like, composed of a substantially semi-circular ring-like member, said member having a part formed to engage the upper half of the headlight and to be held in clamped position thereon by the headlight glass, a substantially horizontal cut-off plate formed to engage over the source of light, and means to rigidly secure said plate to the ends of said member so as to hold said ends spread apart and against movement toward each other.

In testimony whereof I have affixed my signature in the presence of two witnesses.

OTHO M. OTTE.
